No. 653,992.

Patented July 17, 1900.

C. J. E. FLECK.

COUNTING BOARD.

(Application filed Feb. 8, 1900.)

(No Model.)

UNITED STATES PATENT OFFICE.

CARL JACOB EMIL FLECK, OF HAMBURG, GERMANY.

COUNTING-BOARD.

SPECIFICATION forming part of Letters Patent No. 653,992, dated July 17, 1900.

Application filed February 8, 1900. Serial No. 4,552. (No model.)

To all whom it may concern:

Be it known that I, CARL JACOB EMIL FLECK, a subject of the German Emperor, and a resident of Hamburg, in the German Empire, have invented certain new and useful Improvements in Counting-Boards, of which the following is a specification.

The present invention relates to an improved counting-board or counter of the folding type which is more particularly intended for use in connection with the sliding doors or windows of tram-cars or similar vehicles and may also serve as a ticket-delivery or booking-office window or doorway and as a money-receiving counter or table.

The improved folding counter is constructed with two flaps or shutters which when open constitute a table or board of an area equal to about double the area of the aperture in the window or sliding door and is thereby distinguished from the folding counters hitherto in use and constructed with one flap only, which flap or shutter is of about the same dimensions as the opening which it protects or covers, and, moreover, when open presents a table or board projecting at one side only, while with the improved device the flaps project from both sides of the door or window.

In order that my invention may be more fully understood by one skilled in the art to which it appertains, I will now proceed to describe the same in detail, and for that purpose reference is taken to the accompanying sheet of drawings, wherein—

Figure 1 is a vertical section through my improved folding counter, showing the flaps or flap-boards in the closed position. Fig. 2 is a similar view showing the flap-boards opened or respectively in the position in which they serve as a delivery or receiving board, and Fig. 3 is a plan of Fig. 2 according to the sectional line I II.

Similar letters refer to similar parts throughout the several views.

The two parts, flaps, or wings *a* and *b* are arranged in a frame *c*, fixed in the sliding door *d* or window, respectively, of a tram-car and are each of about the same size as the aperture in the said frame. These flaps *a* and *b* are hinged by means of pivots or journals *e* in suitable holes or bearings in the side portions of the frame *c*. On the said pivots *e* or

to the flaps *a* and *b*, respectively, are fixed small toothed pinions *r*, conveniently arranged in suitable recesses at the corners of the flaps, the pinions of the flap *a* gearing together with those of the flap *b*, as this is evident from the drawings. Therefore in pulling or turning one of the flaps downward—for instance, the flap *b*—by means of a knob 60 or handle *f* thereon the other flap *a* by means of the toothed gearing *r* will also be moved or turned downward, and thereby the two flaps *a* *b* are brought to the proper position to serve as a counter or table for the receipt 65 of money or the collection or delivery of tickets or the like. The lower or inner edges of the flaps are so formed and arranged that in this position of the flaps the said edges rest against and support each other along their 70 entire length, and the flaps are thereby kept in a horizontal plane without requiring any other support, the aperture being then open, Figs. 2 and 3. When it is desired to close the said aperture, it is only necessary to turn 75 upward one of the flaps, as in consequence of the gearing *r* both flaps will be closed and turned back into the frame *c* simultaneously. In the closed or raised position, Fig. 1, the flaps may be secured by a spring-catch *g* or 80 other suitable device.

In order that the two leaves *a* and *b* of the counter or table may properly fold together and in order that they may properly abut when unfolded, it is necessary that the said 85 meeting edges be partly curvilinear and partly straight. Obviously such a construction if applied to the full length of the meeting edges would result in a transverse groove or depression formed by the curvilinear or 90 rounded upper edge of said meeting edges. To avoid this and provide a perfectly-plain table when the leaves are unfolded or turned down, I provide them with an upwardly-projecting flange *a'* and *b'*, respectively, preferably 95 encompassing three sides of the leaves, and with a straight downwardly-projecting flange *a²* *b²*, respectively, the meeting edges of the upwardly-projecting flanges alone being rounded, as shown at *a³* *b³*, thus forming a perfectly flat or plain table-top when unfolded, while said upwardly-projecting flanges form guards to prevent money, tickets, or the like from sliding over the table. 100

Having fully described my invention, what I claim, and desire to secure by Letters Patent, is—

1. A folding table or counter comprising a suitable support, a table-top composed of two leaves pivoted to the support and geared together to fold and unfold, said leaves having encompassing flanges on three sides projecting upwardly and downwardly, and a downwardly-projecting flange at their meeting edges, the lateral upwardly-projecting flanges being rounded at their meeting edges to provide clearance in folding, substantially as and for the purpose set forth. 5
2. A folding table or counter comprising a support having a vertical aperture, and a table-top composed of two leaves geared together and pivoted to fold into and close the aperture, substantially as set forth. 15
3. A folding table or counter, comprising a suitable support having a vertical aperture, 20

a table-top composed of two leaves geared together and pivoted to fold in and close said aperture, and a locking device locking the leaves when folded, for the purpose set forth. 25

4. A folding table or counter, comprising a support having a vertical aperture, a framing fitted in said aperture, a table-top comprising two leaves geared together and pivoted to said framing to fold into and close the same, said leaves having upwardly and downwardly projecting flanges encompassing three of their sides, and a downwardly-projecting flange along their meeting edges, the lateral upwardly-projecting flanges being rounded 30 at their meeting edges to provide clearance for folding, substantially as and for the purpose set forth. 35

CARL JACOB EMIL FLECK.
